UNITED STATES PATENT OFFICE.

ARTHUR WILLIAM TIMEWELL, OF LONDON, ENGLAND, ASSIGNOR TO THE SACK-FILLING AND SEWING MACHINE SYNDICATE, LIMITED, OF LONDON, ENGLAND.

FILLED-SACK-SEWING MACHINE.

1,175,571.

Specification of Letters Patent.

Patented Mar. 14, 1916.

Application filed October 30, 1911. Serial No. 657,474.

To all whom it may concern:

Be it known that I, ARTHUR WILLIAM TIMEWELL, a subject of the king of Great Britain, residing at Muscovy House, 6 5 Trinity Square, in the city of London, England, have invented certain new and useful Improvements in or Relating to Filled-Sack-Sewing Machines, of which the following is a specification.

10 This invention relates to improvements in machines for sewing or closing sacks or similar receptacles after the said receptacles have been filled or charged with material and in which the sewing machine head is 15 capable of adjustment relatively to the table or conveyer, and particularly to machines of the type in which the conveyer or traveling table is arranged at the floor level, the object being to facilitate the manipulation 20 and working of such machines, and to adapt the same for being more readily adjusted vertically to accord with the size of the work.

According to this invention the distance 25 of separation of the sewing machine table and the traveling table or conveyer arranged at the floor level may be shortened or lengthened, the arrangement being such that the adjustable bracket carrying the said table 30 is provided with a tail piece or extension which is diverted laterally from the center line of the upper part and which carries one or more pulleys or sprocket wheels engaging with a corresponding number of end- 35 less bands or chains passing over a number of pulleys or sprocket wheels carried by the framing of the machine; said bands or chains serving to impart motion to the sewing machine and the sack feeding chains 40 provided on the machine.

In order that the said invention may be clearly understood and readily carried into effect, I will proceed to describe the same with reference to the accompanying drawings, in which:—

Figure 1 is an elevation of the machine showing the sewing machine and sack conveyer. Figs. 2 and 3 are respectively a rear and side elevation of the machine showing 50 the main framing but with the sewing machine removed. Fig. 4 is a view in plan corresponding to Fig. 1. Fig. 5 is a detail view of the sewing machine. Fig. 6 is a detail view showing the thread feed or tensioning rollers and cutter. Fig. 7 is a plan 55 showing the driving gear for said rollers.

The framing a of the machine is provided with a table a' which is mounted upon a bracket or slide a^2 capable of vertical adjustment in the said framing, the bracket 60 being guided in its movement by the vertical guides a^3 , a^4 (Fig. 2). A convenient means of effecting the movement may comprise an arrangement of chain and chain or sprocket wheels and counter-balance weights or 65 equivalent means. Such an arrangement is shown in Fig. 1, where a^8 is one of a pair of chains each of which has its respective ends connected to the table a' and the counterweight a^9 . The chains pass over and 70 engage with sprocket wheels a^{10} secured to the shaft a^{11} and when this latter is rotated by means of the hand wheel a^{12} the table is moved vertically along the framing of the machine. The bracket a^2 carries fast and 75 loose pulleys a^5 whereby the mechanism mounted on the table a' is actuated by a suitable belt a^6 (Fig. 2), same passing over said pulleys a^5 and the pulleys a^7 carried by the framing of the machine. The bracket 80 is also provided with sprocket or chain wheels b over which passes an endless chain b' . The bracket a^2 is formed or provided with a tail piece or extension b^2 the lower part of which is diverted laterally from the 85 center line of the upper part thereof. The tail piece b^2 carries a pin or stud b^3 on which is mounted a pulley and sprocket wheel intended respectively for the endless belt a^8 and the endless chain b' . A similar pulley 90 and sprocket wheel are mounted on a stud b^4 on the main framing a of the machine so that said tail piece, by passing the pulley and sprocket wheel mounted on the stud b^4 on the machine, effect a shortening or lengthening 95 of the distance of separation of the table a' and the conveyer b^5 without any interruption of the operation of the parts.

The chain b' passes about a sprocket wheel b on a spindle or shaft b^6 mounted on the aforesaid upper table a' , about the sprocket wheel on the pin b^3 at or about the end of the depending extension b^2 of the bracket, thence about the sprocket wheel on the stud b^4 and then about a sprocket wheel c on a 100 lower shaft c^x ; from this last mentioned sprocket wheel the chain b' is carried to the sprocket wheel b adjacent to the table a' . The sprocket wheel b is arranged on the shaft b^6 and this latter is connected to 105 a shaft b^{11} through the gear wheels b^{12} . The shaft b^{11} carries a bevel pinion b^{13} which

engages with another bevel pinion b^{14} , Fig. 4, so as to impart movement to the shaft b^{15} , the motion of this latter shaft being in turn imparted to the shaft b^{16} through the bevel gearing b^{17} . An endless sack feeding chain or band d passes over the shaft b^{16} , and when said shaft is rotated the band d is operated and the mouth of the sack is carried between said band d and an adjacent endless band d^{18} . Motion is imparted to the shaft b^6 from the shaft a^{14} carrying the pulleys a^5 by the intermediate train of gear wheels a^{15} , a^{16} . By this arrangement of the chain b' the necessary actuation of the sack feeding band d , Fig. 6, is effected while a ready means of raising and lowering the table is provided, such means being capable of operation by the hand wheel.

The driving belt a^6 is, in a similar manner to the endless chain b' , arranged to pass over the pulleys arranged on the aforesaid pins or studs b^3 , b^4 so that the raising and lowering of the table a' may be readily effected without disturbing the tension of said belting and the actuation of the sewing machine.

The sack conveyer b^5 is placed in a recess b^7 formed below the floor level so that the upper portion of the endless band b^8 of the conveyer is practically flush with the floor level b^9 and in a convenient position for receiving the sacks to be operated upon. Motion is imparted to the conveyer by means of the sprocket-wheels h , h' (Fig. 1).

In connection with the sewing mechanism c which is carried by the adjustable table a' it is proposed, according to the present invention, to place the looper c' (Fig. 5) above the needle c^2 and to actuate the same directly from the main spindle c^3 of the sewing machine. The needle c^2 is mounted in the bar k and this latter is reciprocated by the eccentric strap k' which receives its motion from an eccentric k^2 carried by the main spindle of the sewing machine. By arranging the looper above the needle any undue weight or tension, as a result of the work in progress, has no detrimental effect on the looper or other part of the mechanism. Any known type of looper may be employed but it is preferable to employ a type adapted to form an ordinary chain stitch. In order to enable the sacks to be dealt with effectively by the sewing mechanism c , whatever the speed or regularity of the feed of the filled sacks may be, it is proposed to provide means for preventing the thread slackening owing to the idle running of the machine. To this end, horizontally revolving rollers c^4 are arranged between the needle and the cutter c^5 , Fig. 6, so that the thread or the chain made by the sewing machine will always be in a state of tension while the machine is working. The rollers c^4 may be actuated from

the feed chain d of the machine or as hereinafter described. They serve to put a tension on the thread and so keep the same taut after the sack has passed and the machine is awaiting the insertion of another sack for being sewn or closed. The spindles d' which carry the rollers c^4 are mounted the one on the table a' and the other on a plate d^2 capable of movement in slots or guides d^5 . The rollers c^4 are actuated by a belt c^6 which is carried by grooved wheels c^7 , c^8 and is driven from the shaft d^x whereon the sprocket or tooth wheel f for the feed chain d is mounted. The roller c^4 mounted on the plate d^2 is so arranged as to be in yielding contact with the sack and the thread or chain constituted thereby, by any suitable means such as springs d^4 or equivalent devices capable of affording a yielding effect. Only one of the rollers c^4 is driven by the belt c^6 , the other roller being in frictional engagement with the former roller and being driven thereby. It will be understood that the operating lever c^9 for the cutter c^5 is connected with the latter in such a manner as to permit of the necessary relative movements.

What we claim and desire to secure by Letters Patent of the United States is:—

1. In a machine for sewing or closing the mouths of filled sacks or similar receptacles, the combination of a sewing-mechanism, a table for said mechanism, a counterweight for said table, chains connected to said table and counterweight, a shaft, sprocket-wheels on said shaft for engaging with said chains, a hand-wheel for rotating said sprocket-wheels and adjusting the vertical position of the table, a sack-conveyer, a pair of co-acting endless bands for feeding the mouths of the sacks, an adjustable bracket carrying the table, an extension on said bracket which is diverted laterally from the center line of the upper part thereof, a stud on said extension, a pulley-wheel and a sprocket-wheel on said stud, a stud carried by the framing of the machine and arranged to the side of the stud on the extension, a pulley-wheel and a sprocket-wheel on said stud and a driving-belt and a driving-chain passing over said wheels and imparting motion to the sewing mechanism and sack-conveyer irrespective of the position of the table of the machine.

2. In a machine for sewing or closing the mouths of filled sacks or similar receptacles, the combination of a sewing-mechanism, a table for said mechanism, a counterweight for said table, chains connected to said table and counterweight, a shaft, sprocket-wheels on said shaft for engaging with said chains, a handwheel for rotating said sprocket-wheels and adjusting the vertical position of the table, a sack-conveyer, a pair of co-acting endless bands for feeding the mouths

of the sacks, gearing for actuating the feeding device for the sack mouths, an adjustable bracket carrying the table, an extension on said bracket which is diverted laterally

5 from the center line of the upper part thereof, a stud on said extension, a pulley-wheel and a sprocket-wheel on said stud, a stud carried by the framing of the machine and arranged to the side of the stud on the extension, a pulley-wheel and a sprocket-wheel on said stud and a driving-belt and a driving-chain passing over said wheels and imparting motion to the sewing mechanism and sack-conveyer irrespective of the position of the table of the machine.

3. In a machine for sewing or closing the mouths of filled sacks or similar receptacles, the combination of a sewing mechanism, a main spindle for said mechanism, a needle for said mechanism, a looper, a table for said mechanism, a counterweight for said table, chains connected to said table and counterweight, a shaft, sprocket-wheels on said shaft for engaging with said chains, a handwheel for rotating said sprocket-wheels and adjusting the vertical position of the table, a sack-conveyer, a pair of coacting endless bands for feeding the mouths of the sacks, gearing for actuating the coacting endless bands for feeding the sack mouths, an adjustable bracket carrying the table, an extension on said bracket which is diverted laterally from the center line of the upper part thereof, a stud on said extension, a pulley-wheel and a sprocket-wheel on said stud, a stud carried by the framing of the machine and arranged to the side of the stud on the extension, a pulley-wheel and a sprocket-wheel on said stud and a driving-belt and a driving-chain passing over said wheels and imparting motion to the sewing

mechanism and sack-conveyer irrespective of the position of the table of the machine.

4. In a machine for sewing or closing the mouths of filled sacks or similar receptacles, the combination of a sewing mechanism, a main spindle for said mechanism, a needle for said mechanism, a looper arranged above the needle and actuated directly from the main spindle, a cutting device for the thread, a tensioning device comprising horizontally revolving rollers placed between the needle and the cutting device, a table, a counter-weight for said table, chains connected to said table and counterweight, a shaft, sprocket-wheels on said shaft for engaging with said chains, a handwheel for rotating said sprocket-wheels and adjusting the vertical position of the table, a sack conveyer, a pair of coacting endless bands for feeding the mouths of the sacks, gearing for actuating the said coacting endless bands, an adjustable bracket carrying the table, an extension on said bracket which is diverted laterally from the center line of the upper part thereof, a stud on said extension, a pulley-wheel and a sprocket-wheel on said stud, a stud carried by the framing of the machine and arranged to the side of the stud on the extension, a pulley-wheel and a sprocket-wheel on said stud and a driving-belt and a driving-chain passing over said wheels and imparting motion to the sewing mechanism and sack-conveyer irrespective of the position of the table of the machine. 75

In testimony whereof I affix my signature in presence of two witnesses.

ARTHUR W. TIMEWELL.
